The ornamental design for a globe for a signal illuminating lamp, as shown and described.

DESCRIPTION

FIG. 1 is a front elevational view of a first embodiment of the globe for a signal illuminating lamp showing our new design;

FIG. 2 is a right side elevational view thereof, the left side elevational view being the mirror image of the right side elevational view;

FIG. 3 is a top plan view thereof, the bottom plan view being the mirror image of the top plan view;

FIG. 4 is a rear elevational view thereof;

FIG. 5 is a front elevational view of a second embodiment of the globe for a signal illuminating lamp;

FIG. 6 is a right side elevational view thereof, the left side elevational view being the mirror image of the right side elevational view;

FIG. 7 is a top plan view thereof, the bottom plan view being the mirror image of the top plan view; and,

FIG. 8 is a rear elevational view thereof.
